UNITED STATES PATENT OFFICE.

FRED A. PUTNAM AND CHARLES F. ROBBINS, OF KEENE, NEW HAMPSHIRE,
ASSIGNORS TO MARKEM MACHINE COMPANY, OF BOSTON, MASSACHUSETTS,
A CORPORATION OF MASSACHUSETTS.

TYPE-WHEEL.

1,376,830.

Specification of Letters Patent. Patented May 3, 1921.

Application filed August 1, 1919. Serial No. 314,709.

To all whom it may concern:

Be it known that we, FRED A. PUTNAM and CHARLES F. ROBBINS, citizens of the United States, and residents of Keene, county of Cheshire, State of New Hampshire, have invented an Improvement in Type-Wheels, of which the following description, in connection with the accompanying drawing, is a specification, like characters on the drawing representing like parts.

This invention relates to type wheels of the character which are used in those printing or marking machines which have a plurality of independently-adjustable type wheels, each bearing a plurality of type characters. As an example of marking machines of this type we would refer to our Patent No. 1,131,865, dated March 16, 1915, and also to United States Patent No. 1,131,959, dated March 16, 1915.

The object of the invention is to provide a novel type wheel for use in marking machines of this character which can be inexpensively manufactured and which will stand up under the usage to which it is put.

In order to give an understanding of our invention, we have illustrated in the drawings a selected embodiment thereof which will now be described, after which the novel features will be pointed out in the appended claims.

Figure 1 is a side view of a type wheel embodying our invention;

Fig. 2 is an edge view of the type wheel;

Fig. 3 is a section on the line 3—3, Fig. 1;

Fig. 4 is a section on the line 4—4, Fig. 1;

Fig. 5 is a perspective view of one of the type-bearing members;

Fig. 6 is a perspective view of a filling member.

We have found from experience that a type wheel in which the type-bearing portions are made of die casting is an extremely serviceable and satisfactory type wheel. It is, however, difficult to make a relatively large type wheel from a single die casting, partly because of the manner in which die castings are made. Moreover, if a relatively large type wheel is made in a single die casting, there is always danger that the type wheel will warp or twist somewhat, thus throwing the type characters out of correct alignment and making the wheel undesirable

for use in a marking machine where a perfect impression is desired.

We have provided herein a novel type wheel which can be made of relatively large size and which has the type-bearing portions thereof made by the die casting process, thus securing the beneficial effect of die casting for this purpose. We accomplish this object by forming the wheel with a center or body portion which may be machined to the correct size and dimensions and with a plurality of separate type-bearing portions which are firmly secured to the periphery of the center or body portion and which are made by the die-casting process. These type-bearing portions of the wheel are relatively small and can thus be made perfectly by the die-casting process, and the resultant effect of the type wheel, therefore, is the same as if the entire wheel had been made of die casting.

In the type wheel illustrated in the drawings the body or center portion is indicated at 1 and the type-bearing portions at 2. This center or body portion 1 has a disk-like shape and it is formed in its periphery with an annular groove 3. The type-bearing portions 2, which are preferably made of die casting, are each formed on their outer end with a type character 4 and are provided with one or more shoulders 5 which rest against the periphery of the body 1 and with a foot portion 6 which fits into the groove 3. Each type-bearing portion 2 is anchored in the groove by means of pins 7 extending transversely through the body 1 and the feet 6.

In the construction shown the type-bearing members 2 are spaced from each other somewhat, said spaces being filled by filling members 8. Each filling member is provided with two shoulders 9 which rest against the periphery of the body 1 and with a foot portion 10 which fits the groove 3. Each filling member is anchored in position by a pin 7. The filling members fill the spaces between the type-bearing members, and when said members are firmly pinned in place, each type-bearing member will be firmly supported on each side by a filling member and the effect will be that of a solid one-piece type wheel. Since the type-bearing portions are of relatively small size,

they can readily be made of die castings and, therefore, our invention provides a type wheel in which the type-bearing portion thereof can be made of die casting regardless of the size of the type wheel.

The filling members 8 can be used as guide or indicating members to assist the operator in setting each type wheel. For this purpose the filling member 8 which is in position to 10 be observed by the operator will have a type character corresponding to that of the type-bearing member which is in printing position.

Our invention may be embodied in type 15 wheels which are constructed to be adjusted in any well-known way. The type wheel herein shown is designed to be adjusted or set by means similar to that illustrated in the above-mentioned United States Patent 20 No. 1,131,959, and is, therefore, made with a central opening 11 through which the supporting sleeve extends and is provided with a plurality of inwardly-directed teeth 12 that are adapted to be engaged by a setting 25 tooth or projection on a spindle extending axially through the sleeves, all as shown in said patent.

The construction herein shown provides a 30 type wheel having interchangeable type characters. This is an advantage because it provides a construction wherein one or more of the type characters on a type wheel can be changed without the necessity of providing an entirely new type wheel. Any one of 35 the type-bearing projections 2 can be readily removed from the type wheel by driving out the pins 7 and such type-bearing portion can be replaced by another type-

bearing portion having a different character thereon. It sometimes happens that one 40 of the type characters on a type wheel will become broken or injured, and with the present construction such defective type character can be removed and replaced by another at a very small expense compared 45 with the expense of an entirely new type wheel.

We claim:

1. A type wheel comprising a disk like body portion having a peripheral groove 50 and plurality of separate type-bearing members having the same thickness as the body and each member having a foot portion of the same width as the main part of the member, each foot portion being anchored in 55 said groove.

2. A type wheel comprising a disk-like body portion having a peripheral groove and a plurality of separate type-bearing members situated exterior to said body and 60 each having a shoulder to fit against the periphery of said body and a foot portion anchored in said groove.

3. A type wheel comprising a disk-like body portion having a peripheral groove, a 65 plurality of separate spaced type-bearing members, each having a shoulder to fit against the periphery of said body, and a foot portion anchored in said groove, and filling members interposed between the type- 70 bearing members.

In testimony whereof we have signed our names to this specification.

FRED A. PUTNAM.
CHARLES F. ROBBINS.
